Primary Examiner — Wan Laymon(74) *Attorney, Agent, or Firm* — Ice Miller LLP(57) **CLAIM**

The ornamental design for an orthodontic elastomeric ligature tie, as shown and described.

DESCRIPTION

FIG. 1 is a front perspective view of an orthodontic elastomeric ligature tie, showing my new design;

FIG. 2 is a front elevational view thereof;

FIG. 3 is a back elevational view thereof;

FIG. 4 is a side elevational view thereof, and the opposite side elevational view is a mirror image of the side elevational view thereof;

FIG. 5 is a top elevational view thereof;

FIG. 6 is a bottom elevational view thereof; and,

FIG. 7 is a front perspective view thereof, wherein the broken line showing of a mouth is for the purpose of illustrating an environment and forms no part of the claimed design.

1 Claim, 5 Drawing Sheets(56)
